DESIGN FOR A DRINKING GLASS

George L. Kearney, Tuckahoe, N. Y., assignor to Geo. Borgfeldt Corporation, New York, N. Y., a corporation of New York

Application March 22, 1943, Serial No. 109,789

Term of patent 7 years

To all whom it may concern:

Be it known that I, George L. Kearney, a citizen of the United States of America, residing at Colonial Heights, Tuckahoe, Westchester County, State of New York, have invented a new, original, and ornamental Design for a Drinking Glass, of which the following is a specification, reference being had to the accompanying drawing, forming a part thereof, and wherein:

Fig. 1 is a perspective view of a drinking glass, showing my new design; and

Fig. 2 is a vertical sectional view thereof.

I claim:

The ornamental design for a drinking glass, substantially as shown.

GEORGE L. KEARNEY.
